UNITED STATES PATENT OFFICE.

GEORGE E. INGRAM, OF CHICAGO, ILLINOIS.

AIR VALVE FOR INTERNAL-COMBUSTION ENGINES.

Application filed October 2, 1923. Serial No. 666,129.

To all whom it may concern:

Be it known that I, GEORGE E. INGRAM, a citizen of the United States, residing in the city of Chicago, county of Cook, and 5 State of Illinois, have invented a new and useful Improvement in an Air Valve for Internal-Combustion Engines, of which the following is a specification.

My invention related to improvements in 10 internal combustion engines, and particularly related to the provision of an air valve arranged to admit or exclude air from the cylinder when the engine is in operation.

The primary object is to provide an im- 15 proved device for controlling the admission air into the cylinders of an internal combustion with a view to reducing the fuel consumption and hence the cost of operation.

20 A further object is to provide an improved construction whereby an air control valve may be resiliently held in position to admit or exclude air for a cylinder as desired, thereby varying the character of 25 a charge without substantially varying the total volume of mixture or decreasing the degree of compression.

A still further object is to provide an improved device of simple and efficient construction which may be easily assembled and operated.

I accomplished these and other objects by means of the device disclosed in the drawings forming a part of the present 35 specification wherein like characters of reference are used to designate similar parts throughout said specification and drawings and in which,

Fig. 1 is a broken vertical section of a 40 cylinder disclosing my improved air valve applied thereto, said valve being shown in the air excluding position.

Fig. 2 is a similar view showing the valve moved to the air admitting position.

45 Fig. 3 is a broken sectional detail showing the arrangement of the air passages and the valve mounting.

Referring to the drawings the numeral 1 is used to designate in general a cylinder of 50 an internal combustion, within which cylinder is mounted the usual reciprocating piston 2.

An air port 3 is formed in the side of the piston, and seats are formed upon the inner 55 and outer sides of port as at 4 and 5. A

valve stem 6 is slidably mounted within said port and valves 7 and 8 secured in spaced relation upon said stem to engage the seats 4 and 5 respectively for different positions of the stem 6, said stem being carried within 60 a bearing 9 centrally disposed within the port 3.

The stem 6 is provided with an outwardly extending end 11 having a slot 12 formed therein. An actuating member 13 is slidably mounted upon the outer side of the cylinder adjacent the outwardly extending end 11, and a spring 14 is secured upon 65 said actuating member and arranged to engage the slot 12. The actuating member 70 is preferably mounted upon a cap 16 secured upon the cylinder to cover the port 3 and the valves, an aperture 17 being formed in said cap to communicate with the atmosphere and admit air into the cap 75 and to the port 3 in a manner hereinafter more fully described.

The spring 14 is preferably a flat leaf spring normally disposed in angular relation to the actuating member 13 so that 80 when the actuating member is elevated to its upper position as shown in Fig. 1 of the drawings the outer end of the spring will force the stem 6 inwardly and cause the outer valve 8 to engage the seat 5 and 85 be held resiliently thereagainst. When the actuating member is depressed the spring 14 will cause the stem to be moved outwardly to normally hold the inner valve 7 in resilient engagement with the seat 4 as 90 shown in Fig. 2 of the drawings.

The port 3 preferably consists of a pair of arcuate pasages arranged upon opposite sides of the bearing portion 9 above mentioned, said passages being adapted to be entirely closed when either valve 7 or 8 is seated in normal position.

The operation of my invention is as follows: In starting the engine, the actuating member is moved manually by means of any appropriate connections, not shown, mounted in a position readily accessible to the operator, to the position shown in Fig. 1 of the drawings whereby the stem 6 is moved to seat the outer valve 8 upon its seat 5, and resiliently held in such position by the outer end of the spring 14. When now the piston 2 is reciprocated in the usual manner within the cylinder, the valve 8 will prevent air from being drawn into the cylinder through 110

the passage 3 during the intake stroke. During the compression and firing strokes of the piston the internal pressure effective against the face of the valve 7 will force said valve 5 to engage the seat 4, and prevent the escape of the combustible mixture supplied therein through the intake in the ordinary manner, the valves 7 and 8 being moved outwardly against the pressure of the spring 14. In 10 this manner a rich mixture of gas is drawn into the cylinder through the usual intake 18 for setting the engine into motion.

After the engine has been set in motion, the actuating lever is moved to the position 15 shown in Fig. 2 of the drawings, the spring 14 being thereby depressed to move the valves outwardly as shown. In this position the outer valve 8 is unseated and the inner valve held in resilient engagement with the seat 4. 20 When now the piston descends upon its suction stroke, the suction created will lift the valve 7 slightly from its seat, the valves being moved against the resistance of the spring so as to permit the entrance of air past the 25 outer valve 8. The inclined arrangement of the spring 14 prevents the valves from being moved sufficiently to cause the outer valve to become seated upon the seat 4, due to the fact that in this position the stem engages the 30 spring near the point of attachment thereof upon the member 13. The air drawn past the valve 8 will of course become mixed with the charge of gas drawn in through the intake 18 and will be compressed therewith 35 upon the succeeding compression stroke of the piston. In this manner the suction effective in drawing in the charge of gas will be reduced and at the same time air will be admitted to the cylinder to dilute the charge 40 of gas without reducing the degree to which the mixture within the charge is compressed. During the compression and firing strokes the internal pressure will cause the inner valve 7 to seat and thus prevent the escape 45 of gas from the cylinder.

From the above description it will be seen that I have provided a simple and effective means for causing the introduction of air into the cylinder independently of the gas intake. 50 This arrangement is of particular advantage in connection with automobile engines. In this connection, the valve is moved to exclude air from the cylinder while the engine is being started and until the automobile has 55 been set in motion. When the desired speed has been attained the momentum acquired carries the automobile forward with the application of but a relatively small amount of power. Under this condition the valve is 60 moved to the air admitting position so that air will be introduced into the cylinder simultaneously with the charge of gas, the amount of gas being reduced and diluted accordingly. By thus admitting air the total 65 volume of gas within the cylinder is main-

tained practically constant so that the diluted charge will be compressed to substantially the same degree as the richer charge used in starting. As increased efficiency is thus obtained from the gas and power thus 70 obtained from a reduced amount of gas sufficient to keep the automobile in motion at the desired speed. In event the load is increased, as when ascending a grade, the valve may of course be moved to the air excluding position and permit the full rich mixture to be drawn into the cylinder. 75

While I have shown what I now consider to be the preferred form of my invention, it will of course be noted that the device may 80 be modified as to form, construction, and arrangement in a great number of ways without departing from the spirit of my invention, I therefore do not wish to restrict myself closely to the particular construction 85 shown but desire to avail myself of all modifications which may fall within the scope of the appended claims.

Having thus described my invention what I claim as new and desire to secure by Letters Patent is— 90

1. The combination with a cylinder of an internal combustion engine, said cylinder having an opening therein, and seats formed upon the inner and outer walls of the cylinder adjacent the opening, of valves carried upon a common valve stem slidably mounted within the opening; and means for moving said valve to normally open or close said opening to admit or exclude air from the cylinder as desired. 95

2. The combination with a cylinder of an internal combustion engine having a valve port therein, of a valve slidably mounted within said valve port; an actuating member slidably mounted adjacent the cylinder; and means carried by the actuating member for normally holding the valve in an open position when the actuating member is in one position, and to normally hold the valve 100 in a closed position when the actuating member is in another position whereby air may be admitted or excluded from the cylinder as desired. 105

3. The combination with a cylinder of an internal combustion engine having a valve port therein, of a valve slidably mounted within said port; an actuating member slidably mounted adjacent the cylinder; and a spring secured upon said actuating member and engaging the valve to normally hold said valve in an open position when the actuating member is in one position, and to normally hold the valve in a closed position when the actuating member is in another position to admit or exclude air from the cylinder as desired. 115

4. The combination with a cylinder of an internal combustion engine having a passage 120 in the wall thereof and valve seats formed 125

upon the inner and outer extreme of said passage, of a valve stem slidably mounted within said passage, one end of said stem extending outwardly from the cylinder; 5 valves mounted in spaced relation upon said stem and arranged to engage the valve seats; and resilient means for moving said stem to cause a desired valve to engage its seat whereby said valves may be caused to admit 10 or exclude air from the cylinder as desired when the engine is in operation.

5. The combination with a cylinder of an internal combustion engine, said cylinder having a valve passage formed in the wall 15 thereof and valve seats formed upon the inner and outer sides of the wall adjacent the passage, of a valve stem slidably mounted within the passage, one end of said stem

extending outwardly from the cylinder; a pair of valves mounted in spaced relation 20 upon said stem and adapted for engagement with the valve seats, said valves being arranged to be independently seated for different positions of the stem; an actuating member slidably mounted upon the outer 25 side of the cylinder; a spring secured upon the actuating member and slidably engaging the outwardly extending end of the stem whereby said stem may be moved to cause either valve to be normally held in resilient 30 engagement with its valve seat to admit or exclude air from the cylinder when the engine is in operation.

In witness whereof I hereunto set my signature.

GEORGE E. INGRAM.
